DESIGN FOR A TUMBLER RACK

Adolph J. Havlis, Oak Park, Ill., assignor to Keystone Metal Products Co., Chicago, Ill., a corporation of Illinois

Application September 12, 1940, Serial No. 94,991

Term of patent 3½ years

To all whom it may concern:

Be it known that I, Adolph J. Havlis, a citizen of the United States, residing at Oak Park, in the county of Cook and State of Illinois, have invented a new, original, and ornamental Design for a Tumbler Rack, of which the following is a specification, reference being had to the accompanying drawing forming a part thereof.

In the drawing:

Figure 1 is a front elevational view of a tumbler rack, showing my design;

Figure 2 is a side elevational view of the tumbler rack shown in Figure 1; and

Figure 3 is a top plan view of the tumbler rack.

I claim:

The ornamental design for a tumbler rack, substantially as shown.

ADOLPH J. HAVLIS.
